Primary Examiner — Deanna L Pratt

(74) Attorney, Agent, or Firm — Banner & Witcoff, Ltd.

(57) **CLAIM**

The ornamental design for a cabana, as shown and described.

DESCRIPTION

FIG. 1 is a front, left perspective photographic view of a cabana showing our new design;

FIG. 2 is a front photographic view thereof;

FIG. 3 is a rear photographic view thereof;

FIG. 4 is a right side photographic view thereof; and,

FIG. 5 is a left side photographic view thereof.

The broken lines depicting the remainder of the cabana form no part of the claimed design.

1 Claim, 5 Drawing Sheets
